UNITED STATES PATENT OFFICE

2,018,158

FOUNTAIN TOOTHBRUSH

Richard J. Violette, Virginia, Minn.

Application April 20, 1933, Serial No. 666,997

4 Claims. (Cl. 15—137)

This invention relates to fountain toothbrushes, the principal object being to provide a more practical and efficient brush of this type than heretofore known.

5 Another object is to provide a fountain brush of this character having a novel form of discharge nozzle in the midst of the bristles of the brush.

A further object is to provide such a brush 10 requiring a specific form of container tube for same; the tube having means whereby to prevent any possible leaking or daubing of the handle portion of the brush, and one especially simple of manipulation.

15 A still further object is to provide a novel form of jack or thrust mechanism for the extrusion press of such a brush.

Other objects and advantages of the invention will appear in the following description there- 20 of.

Referring now to the accompanying drawing, forming part of this application, and wherein like reference characters indicate like parts:

Figure 1 is a longitudinal sectional view of one 25 of the complete brushes with a dentifrice tube therein.

Figure 2 is a transverse section on the line 2—2, Figure 1.

Figure 3 is a plan view of the bristle end of 30 the brush showing the position of the nozzle there- within and the bristles removed.

1 represents the handle of the brush which is preferably circular externally, though may be of any other desired shape if preferred. This handle 35 portion is provided with two separate chambers; the major one for the convenient reception of the dentifrice tube 3, and the minor one, indicated at 4, for the reception of the telescopic jack or thrust mechanism, the component parts of 40 which are indicated at 5, 6, 7, 8, and 9, which will be more fully described later. This handle portion 1 is provided with a closure plug 10, screw-threadedly mounted therewithin, and rotatably carries axially thereof, the jack operated 45 cap 11.

Into the opposite end of the handle 1 is screw-threadedly mounted the arcuately shaped brush shank 12, it being so constructed as to receive the discharge end of the dentifrice tube and form 50 a flush, tapered, continuation of the round handle. This brush shank is hollow and so formed as to discharge centrally of and into the group of bristles 13 of the toothbrush. For such discharge I have shown illustrated as at 14 a soft 55 rubber nipple or nozzle, the same being provided

with a simple, central, slit 15 in the face thereof so as to freely discharge the dentifrice when under pressure, but which will automatically close by its inherent resiliency, thus insuring against remaining open and fouling within the brush when not desired; and which tip or nozzle may be secured within the brush in any desired manner.

The dentifrice tube is illustrated at 3, and is 10 of suitable rigid material to withstand ordinary abuse in handling, and designed to snugly fit within the elliptically shaped bore of the handle. This bore or barrel is provided especially for the purpose of preventing turning of the tube when inserted within the handle.

15 The forward end of the dentifrice tube is provided with an annular inclined shoulder as at 16 so as to snugly fit the lesser inclined shoulder 17 of the socket end of the brush shank 12 to insure against leakage of the dentifrice, and which shoulder is further continued at a lesser angle forming a tapered neck 21 on the tube. This neck is internally screw-threaded for any suitable form of cap or plug not shown, but which tapered neck 25 is desired to fit snugly within the soft rubber fillet 26 or washer 18 installed within the socket end of the brush shank, so that when the dentifrice tube is thus installed within the handle of the toothbrush it is positively insured against leakage about such connection.

30 Now the rear end of the tube 3 is equipped with a concaved metal or other semi-rigid follower 19, it being so shaped as to receive the beveled face 20 of the plunger 21, and about its innermost inclined edge is provided with a suitable yieldable 35 washer 22 or packing ring which tends to slightly expand when pressure is applied thereto by the thrust of the dentifrice thereagainst, and also insured against leakage thereabouts when the extrusion press is forced forward.

40 This piston or extruder 21 is, of course, elliptical in shape to register properly with the compression ring or follower 19, and upon the opposite extremities of its larger diameter is slightly inclined so as to engage a beveled or chamfered 45 recess 23 upon the similarly opposite ends of the rearmost extremity of the tube chamber; this being for the purpose of insuring at the return stroke of the plunger that it register uniformly within the elliptically shaped end of the 50 chamber.

45 The extruding mechanism or telescopic jack, as previously described, comprises the internally screw-threaded members 5, 6, 7 and 8, with the centermost plunger stem 9 having an enlarged 55

head 24 screw-threadedly mounted within the member 8, and the other member 5 of the jack has a solid head carrying axially thereof the bolt 25 of the cap 11 so that when the cap is 5 turned as by the thumb and finger of the operator the other member of the jack will also be turned, thus causing any or all of the cooperating members to similarly turn one within the other, and their frictional engagement may 10 permit it being optional as to which one does the turning, so long as the plunger stem is prevented from turning. The plug 10 is provided with slightly enlarged oblique faces upon either side thereof to reduce the frictional engagement of 15 the cap and the head of the outer jack member 5, which is obvious, and it is clear from the above description that the turning of the cap 11 will force the plunger 21 into the concaved seat of the follower 19 of the dentifrice tube. Also that 20 when the cap 11 is turned in the opposite direction it will cause the jack to retract to its fully retracted position within the chamber, and with the plunger 21 drawn fully back free from the end of the tube. Assuming the tube to have 25 been emptied by the use of the device, if the handle portion 1 is unscrewed from the shank 12 of the brush, the neck of the tube is conveniently available for extraction and another tube installed within the handle, when the device 30 may be again assembled and ready to function as before.

It is further obvious that by unscrewing of the bolt 25 the cap 11 may be removed, when the plug 10 is accessible as by a suitable wrench, 35 and when the latter is removed, the jack or extruding mechanism may also be conveniently taken out for repair or renewal as desired.

A removable cap or cover is illustrated at 28 which may be slipped over the brush end of the 40 device and be frictionally held thereupon by engagement with the brush carrying shank; the cap or cover being perforated to allow circulation of air through the bristles, for obvious reasons.

Having thus described my invention, what I claim and desire to secure by Letters Patent, is:

1. A fountain tooth-brush comprising in combination a hollow handle portion the interior of which is divided into two communicating chambers, a dentifrice tube removably carried in the major one of said chambers, and a dentifrice extrusion press carried within the minor one of said chambers and cooperatively engageable with the tube. 10

2. In a fountain tooth-brush having a hollow handle, a removable dentifrice tube carried within said handle, an impervious reciprocable follower forming the bottom of said tube and providing means for discharging the contents 15 thereof, an extrusion press having a beveled-edged plunger carried by said handle and engageable against said follower for forcing the contents therefrom, and means for preventing rotation of the follower within the tube. 20

3. A fountain tooth-brush of the character described comprising a hollow cylindrical handle carrying a selectively reciprocable extrusion press therein having a convex plunger, and a dentifrice tube for insertion within the handle 25 characterized by carrying, independently of the handle, a reciprocable concavo-convex disc for engagement by the press plunger when in the handle for discharging the contents thereof to the brush. 30

4. A fountain tooth-brush including a hollow handle having a pair of axially aligned compartments, one of which is non-circularly shaped, a dentifrice tube having an impervious reciprocable bottom within the non-circular compartment, a collapsible extrusion press within the circular compartment having a plunger extendible within the non-circular compartment for engagement with said bottom for forcing the contents from the tube. 40
